United States Patent Office

Des. 188,287
Patented June 28, 1960

188,287

PITCHER

Robert O. Burton, Chicago, Ill., assignor to Aladdin Industries, Incorporated, Nashville, Tenn., a corporation of Illinois

Filed Dec. 30, 1959, Ser. No. 58,858

Term of patent 14 years

(Cl. D44—21)

Fig. 1 is a side elevational view of a pitcher, showing my new design;

Fig. 2 is a front view thereof; and

Fig. 3 is a top plan view.

I claim:

The ornamental design for a pitcher, as shown.
